UNITED STATES PATENT OFFICE.

WILLIAM AUBERLIN, OF NORTHFIELD, OHIO.

PROTECTING AND SAFETY NET FOR THE ANCHORAGES OF DIRIGIBLES.

Application filed June 27, 1927. Serial No. 201,906.

This invention relates to air-ship anchorages, and has an improvement on the addition to the anchorage shown in my U. S. Patent No. 1,629,197, dated May 17, 1927.

5 The object of the present invention is to provide a protecting or safety net for the anchorages of dirigibles, which will assist in mooring a ship to the anchorage and holding the same thereto after being moored, so that 10 it will outride gales and be held firmly and in correct position.

As will be appreciated, the mooring of a dirigible balloon to a mast or anchorage is a matter of considerable difficulty particularly in a high wind. By means of the present invention the operation is assisted, and the front part of the airship will enter the net suspended on the anchorage, as it is drawn toward the mooring mast, and this net 20 will serve to center and guide the air-ship to its proper position and to hold the same therein after it is made fast.

The invention will be more fully understood from the following description and the 25 accompanying drawings in which Figure 1 is a side elevation of the apparatus. Fig. 2 is a top plan view thereof.

In the drawings, 6 indicates a base on which is mounted a turn table 7 and a V-shaped wind shield 8 behind which is the 30 mooring mast 9. A cable 10 extends from a winding drum 11 over guide pulleys up through the mast and over a pulley 12 at the top, and in mooring a ship this cable will 35 be run out a sufficient distance to be hooked to the nose of the ship. These parts are substantially the same as shown in my patent before referred to.

The present invention comprises a ring 40 shaped net consisting of two sections 13 and 14 connected to a large relatively rigid ring 15. The outer section 13 has a rather large or wide spread. The inner end section 14 is of proper shape and size to fit the barrel or 45 front part of the balloon rather closely. These nets are spread or stretched by means of the plurality of cables 16 connected thereto at opposite sides and running over guide pulleys 17 to winches or pulling devices 18 50 mounted on the turntable. The pulleys 18 are supported by booms or outriggers 19 which diverge from the wings of the wind shield 8 to which they are fastened as shown

at 20, and the outer ends are braced by stays 21 connected to struts 22 and to the wings of 55 the wind shield. Any suitable system of bracing may be employed.

The operation is as follows:

As the airship approaches the anchorage the cable 10 will be laid out through the net 60 for a distance of approximately one thousand feet, and the end of said cable 10 is hooked to the cable 10' suspended from and fastened to the nose of the airship. To assist in properly guiding the bow of the ship 65 into the net there is provided a cable or rope 23 which is fastened to the stern of the ship and another cable or rope 23' which is fastened to the bow of the ship, both of which hang suspended from the ship; furthermore, 70 there are cables or ropes 24 and 24' which are fastened to the ring 15 and which are suspended to the ground and which serve to enable the land crew to hold in check the tension of said ring 15 while the bow of the 75 ship is being directed into the net. The cable 10 is wound in and the bow of the airship will enter the net and passing into the same will distend it until the ring 15 and section 14 fit the nose closely, and as it continues to be drawn in the cables 16 will be tightened, and at last the net and all the 80 cables will be drawn taut and the mooring cable being made fast the airship will take its position directly behind the wind shield 85 and the net will serve to retain it in that position under all conditions, and will to a large extent prevent whipping or pitching of the ship in high or shifting winds. As will be understood the turn table will swing 90 to keep the point of the wind shield into the wind.

The device will be found particularly useful in assisting the mooring of a ship under unfavorable wind conditions. Various 95 changes may be made in the apparatus within the scope of the invention.

I claim:

1. The combination with a wind shield mounted on a turn table and provided with 100 a mooring mast and cable, of an annular net supported by the wind shield, behind the mast, and adapted to receive the bow of a dirigible moored to the mast.

2. The combination stated in claim 1, the 105 net being supported by booms projecting

rearwardly from the wings of the wind shield.

3. The combination stated in claim 1, the net having a section adapted to closely fit around the bow of the dirigible.

4. The combination stated in claim 1, the net having an inner section adapted to closely fit the bow of the dirigible, and an outer flaring section leading thereto.

10 5. The combination stated in claim 1, the net having an inner section to fit the bow of

a dirigible, an outer flaring section, and an intermediate comparatively rigid section.

6. The combination stated in claim 1, the supporting means for the net including 15 booms projecting from the wind shield, and cables connected to the net, the outer ends of the booms being provided with pulleys over which the cables pass.

In testimony whereof, I do affix my signature. 20

WILLIAM AUBERLIN.
